BOTTLE HOLDER

Thomas Holman Bryant, Sr., Louisville, Ky., assignor to Frankfort Distilleries, Incorporated, Louisville, Ky., a corporation of West Virginia

Application October 21, 1940; Serial No. 362,148

5 Claims. (Cl. 206—44)

The present invention relates to improvements in bottle holders and is a continuation in part of my similarly entitled copending application filed August 7, 1940, Serial No. 351,710.

More particularly the invention relates to a device which is adapted to be installed in a carton for receiving the bottle to substantially lock such bottle against rotation.

Although obviously applicable to other uses, the invention is the solution of a problem encountered with round whiskey bottles shipped in square cartons where the whiskey bottle contains front and back labels intended to be observed through front and rear windows in the carton.

Heretofore, it has been found that when shipping the round quart or other size bottle in a square carton with a window in the front of the carton through which the front label should show, it has always been my experience that the bottle turns or rotates while in transit so that sometimes the back label would be showing through the front of the carton and therefore the front label through the smaller opening in the back of the carton. This is an extreme case but the bottle is rarely in the correct position which is extremely undesirable from a sales and advertising view point, and the lack of registry of the bottle labels with the carton openings detracts from the appearance of the package.

From a Federal regulation standpoint, while it is not absolutely necessary that the labels align with the carton openings, it is very desirable that this situation should always obtain to always reveal the mandatory information on the whiskey labels so as to avoid the necessity for taking the bottle out of the carton or turning it to a correct position where such information may be read from the front and back bottle labels.

An object of the invention is to eliminate these inconveniences and to promote the appearance of the package from a sales and advertising standpoint, and also to at all times plainly exhibit the trademark borne by the labels.

Another object of the invention is to provide a device for carrying out the above purposes without in any way introducing alterations to the construction of either the bottle or the carton in which it is contained, the novel device consisting of a separable platform manufactured separately from the carton and readily introducible therein to receive the bottle when the filled bottle is placed in the carton, the arrangement being such that the platform or bottle holder will be concealed by the walls of the carton so

that while performing its function it will make no appearance at all.

A still further object of the invention is to so construct and arrange this platform that it will present parts extending beneath the bottle and on which the weight of the bottle rests to avoid the platform casually or accidentally crawling or creeping upwardly of the bottle to a position where the platform might undesirably show through one of the windows of the carton.

With the foregoing and other objects in view, the invention will be more fully described hereinafter, and will be more particularly pointed out in the claims appended hereto.

In the drawing, wherein like symbols refer to like or corresponding parts throughout the several views.

Figure 1 is a front elevation, with parts broken away and parts shown in section, of a whiskey package with a bottle holder installed therein constructed in accordance with the present invention.

Figure 2 is a rear elevational view of the same with parts broken away and parts shown in section.

Figure 3 is a vertical section taken on the line 3—3 in Figure 1.

Figure 4 is a horizontal section taken on the line 4—4 in Figure 1.

Figure 5 is a bottom perspective view of the improved bottle holder, and

Figure 6 is a fragmentary perspective view of the same.

Referring more particularly to the drawing, 10 designates a conventional round type of whiskey bottle quite commonly in use having the front label 11 and the rear label 12. The cylindrical wall of such bottles is ordinarily tapered downwardly. In other words such bottle is a section of an inverted cone, the removed apex of which projects downwardly.

Such bottles are or may be contained in cardboard or other cartons 13. Such cartons may be square as shown in Figure 4 and contain in the front walls thereof a large opening 14 through which the front bottle label 11 is visible and a smaller opening 15 in the rear wall through which the rear bottle label 12 shows.

The rotation of the bottle 10 in the carton obviously disturbs the alignment and registry of the bottle labels 11 and 12 with their respective carton openings or windows 14 and 15.

To lock the bottle against rotation the device shown in Figure 5 is inserted in the bottom of the

carton and is adapted to receive the lower portion of the tapering wall of the bottle.

Such device consists generally of a platform 16 having a round opening 17 into which the lower end portion of the bottle 10 is adapted to frictionally fit by virtue of the weight of the bottle. The platform 16 is held elevated above the bottom of the carton by suitable legs or flanges 18, 19, 20 and 21. These legs or flanges may be originally stamped out of a flat piece of cardboard or other stock in the same operation with piercing out the opening 17; such legs or flanges being afterwards bent down on the lines of flexure 22, 23, 24 and 25.

One or more flaps, preferably two such flaps 31 and 32, are carried by the platform device, being preferably made from the same piece of cardboard and advantageously extending off opposed legs or flanges 20 and 21. These flaps 31 and 32 are bent along lines of flexure 33 and 34 to enable such flaps 31 and 32 to occupy a position substantially parallel with the platform 16 but disposed in a plane substantially below said platform. The flaps or wings 31 and 32 are sufficiently wide to overlap the opening 17 when projected down to the plane in which the flaps 31 and 32 lie; this being for the purpose of bringing the flaps 31 and 32 beneath the bottle which is insertible through the opening 17 in order that the bottom of the bottle may rest upon the flaps 31 and 32 as shown more particularly in Figure 2. The weight of the bottle will prevent the platform device as a whole from riding up on the external cylindrical wall of the bottle to an undesirable position where the platform device might show through one of the carton openings 14 or 15 or might even crawl or creep up on the labels 11 or 12. Due to the tolerance necessary in the manufacture of folding cartons, holders without such flaps 31 and 32 have been found to crawl or creep up the bottle so that they show through the cutout in the carton, which is undesirable. These flaps 31 and 32 are therefore so relatively arranged in the carton and with reference to the bottle that the weight of the bottle will sit on these flaps and hold the bottle holder in position.

In the use of the device, the bottle holder is manufactured separately of the substantially square shape shown in Figure 5 to accord with the internal measurement of the cross-sectional square carton 13. Such holder is introduced into the bottom of the carton with the platform 16 up and the legs or flanges directed downwardly. The square form of the carton and holder will prevent the holder from rotating therein. The bottle 10 is then introduced into the carton in the usual manner and is tapered side wall will enter the opening 17 which will be made of such diameter that it will just receive the lower end of the bottle but that further movement of the bottle through the platform 16 will cause tight frictional engagement between the wall of the opening 17 and the side wall of the bottle before the bottom of the bottle reaches a rest position upon the bottom of the carton 13. The nature of the cardboard material out of which the platform 16 is made will tend to exert a tight frictional resistance to rotary action upon the wall of the bottle, counteracting any tendency of the smooth glass to rotate. Moreover due to the cardboard nature of the platform 16 the wall of the opening 17 will tend to spread and to thicken out against the wall of the bottle thus promoting a large area of frictional contact.

The cardboard also possesses some degree of resiliency and this resiliency will react against the wall of the bottle. Thus the wedge or tapered formation of the bottle wall will tend to wedge itself in the platform and reacting thereagainst, the inherent resiliency of the material of the platform will tend to resist this wedging action and bind tightly against the tapering wall of the bottle. On the stock round quart whiskey bottle the size of the opening 17 is made so that the holder will go up on the tapered bottle approximately three-quarters of an inch and above this point it will not go. For the fifth size bottles the opening 17 would be proportionately smaller. When the package is complete it will be impossible to turn the bottle with ordinary hand pressure after the bottle has been placed in the holder so that if the labels are lined up with the carton windows at the point of packaging, this alignment will be preserved throughout the transportation of the package. When the package arrives at its destination and is displayed and sold the labels will remain in the original aligned position.

The invention will also be applicable to single window cartons or to single label bottles. In case of round cartons the holder might be secured by adhesive or other means against rotating in such a carton.

The fact that the flaps 31 and 32 are carried by the bottle holder or platform device and extend horizontally beneath the bottle forming a false bottom on which the bottle rests will prevent the platform 16 from riding up very far and the cardboard material may be selected for its friction qualities in which case the flaps 31 and 32 in that area thereof contacted by the bottom of the bottle will exert a substantial frictional influence resisting any tendency of the bottle to rotate.

The device may be economically stamped out of flat cardboard stock to shape, shipped flat for economical transportation and easily and quickly set up by inexperienced labor at the point of packaging.

It is obvious that various changes and modifications may be made in the details of construction and design of the above specifically described embodiment of this invention without departing from the spirit thereof, such changes and modifications being restricted only by the scope of the following claims.

What is claimed is:

1. In a whiskey package, the combination with a carton having a window and a round bottle having a label to show through said window, of a bottle holder removably mounted in the bottom of said carton and comprising a platform having an opening therein to receive the wall of the bottle, and supports for the platform to hold such platform above the bottom of the carton.

2. In a whiskey package, the combination with a square carton having windows in its front and back walls and a round whiskey bottle having front and rear labels adapted to show through the front and rear windows, said bottle also having a tapered wall tapering downwardly, of a bottle holder made independently of said carton and removably introduced into the bottom portion thereof, said bottle holder comprising a square platform of a resilient material adapted to spread and having an opening in said platform to ride up on the tapered wall of the round bottle.

3. In a bottle package, the combination with a carton having a window in its side wall and a bottle received in said carton and having a label adapted to show through the window in the carton, of a bottle holder platform removably disposed in the bottom portion of said carton and held therein against rotative movement with respect to said carton, said platform having an opening therein to frictionally receive the bottle, legs carried by the platform to support it in spaced relation to the bottom of the carton, and flaps connected to the platform and adapted to rest upon the bottom of the carton, said flaps extending beneath the bottom of the bottle to anchor said platform against movement away from the bottom of the carton.

4. The combination with a carton square in cross-section with a window in one of its side walls and a round bottle received in said carton and having a label adapted to show through the window on the carton, of a bottle holding platform disposed in the bottom portion of said carton, said platform being square and of a size corresponding to the internal dimension of said carton, said platform having an opening there-

in to frictionally receive the lower end of the bottle and secure it against rotative movement, legs carried by the platform to support it in spaced relation to the bottom of said carton, and flaps carried by some of said legs and adapted to rest upon the bottom of said carton, said flaps extending beneath the opening in the platform, said bottle extending through the opening in the platform and resting upon the flaps to anchor the flaps and platform against movement away from the bottom of said carton.

5. In a whiskey package wherein a square carton is provided with a window in one of its side walls and a round bottle having a label is positioned in the carton to show the label through the window, the combination with said package of means disposed in the bottom portion of the carton to frictionally receive the wall of the bottle and retain the bottle against rotative movement and the label in substantial registry with the window in the carton, said means also being held against rotative movement with respect to said carton.
